UNITED STATES PATENT OFFICE.

CHARLES F. WILSON, OF DALLAS, TEXAS.

WATER HEATER.

1,411,466.

Specification of Letters Patent.

Patented Apr. 4, 1922.

Application filed March 14, 1921. Serial No. 452,102.

To all whom it may concern:

Be it known that I, CHARLES F. WILSON, a citizen of the United States, residing at Dallas, in the county of Dallas and State of Texas, have invented a new and useful Water Heater, of which the following is a specification.

This invention relates to new and useful improvements in water heaters.

10 The object of the invention is to provide a highly improved water heater of the type that is submerged in water in a bath tub, wash tub, or other like receptacle. A further object of the invention is to provide 15 such a heater that will have an increased circulation of the water through the same, thereby causing the water to heat more rapidly. A further feature is to provide for a free and unobstructed passage of the water 20 through the heater, which will promote circulation. Another object of the invention is to provide a heater simple in construction and comparatively inexpensive to produce.

25 A construction designed to carry out the invention will be hereinafter described together with other features of the invention.

The invention will be more readily understood from a reading of the following specification and by reference to the accompanying drawings, in which an example of the invention is shown and wherein:

Fig. 1 is a side elevation with a portion broken away, of a water heater constructed 35 in accordance with my invention, and disposed in a bath tub,

Fig. 2 is a plan view of the same,

Fig. 3 is a cross-sectional view taken on the line 3—3 of Fig. 2,

40 Fig. 4 is an elevation partly in section of another form of water heater, constructed in accordance with my invention and disposed in a wash tub, and

Fig. 5 is a plan view of the same.

45 In the drawings the numeral 1 designates a bath tub containing water to be heated and in which the heater is placed. The tub or other receptacle in which the heater is placed may contain a greater or lesser amount of 50 water, provided the top of the heater is permitted to extend above the water, as is shown in Fig. 1.

A rectangular hollow base 2 is slightly elevated by means of a flange 3, however said 55 base may assume any practical shape. Extending upwardly from the bottom of the

base is an inner shell 4, which forms a central water channel or well in the heater. A tapering outer shell 6 extends upwardly from the top of the said base, thereby forming a concentric flue 6^a between the inner and outer shells. The outer shell is set inwardly from the edge of the top of the base. Draft pipes 7 extend upwardly from this marginal portion of the top of the base and are inclined in harmony with said shell. The draft pipes permit the passage of air down through the same into the base.

A plurality of ports 5 are provided in the flange 3 permitting the water to pass under 70 the base 2 and up into the central channel. In the flue 6^a a plurality of horizontal radial tubes 9 are disposed in staggered relation to each other, the ends of the tubes engaging in opposite apertures in the inner 75 and outer shells, thus permitting the water from the central channel to pass through the said tubes to the outside of the heater. These tubes are made of such size as to permit a free and rapid passage of the water 80 as well as to provide ample heating surfaces. A gas burner 8 is disposed in the base 2 under the flue, and is supplied with fuel through a feed pipe to which is connected a gas supply pipe.

85 When the heater is in operation a draught of air will be drawn down through the draft pipes 7 into the base 2, thus mixing with the gas emitted by the burner 8 and causing a more ready combustion. The heat products 90 pass up the flue 6^a, thus heating the inner and outer shells 4 and 6, as well as the tubes 9, whereby a large area is exposed thereto. A particular feature of the invention resides 95 in the construction of the said flue, the area of which, due to the tapering outer shell, is reduced towards the top, thereby affording a tendency to accelerate the circulation of the heat. The circulation of air and heat is indicated by the dotted line arrows in 100 Fig. 3.

It is pointed out that water will freely circulate under the base 2 through the ports 5, and pass up into the central channel and out through the tubes 9, as indicated in Fig. 3 by 105 full line arrows. As the water circulates in this manner it is obvious that it will be heated in a very short time. The large entrance at the bottom of the channel affords a free passage of the water and a rapid displacement thereof, which makes for quick 110 heating.

In Figs. 4 and 5 I have shown another form of the invention having a general cylindrical shape and adapted for immersion in vessels of corresponding shape. A cylindrical base 2' has a depending flange 3' provided with ports 5'. A cylindrical inner shell 4' is surrounded by an outer cylindrical shell 6', whereby an annular flue 16 is formed therebetween. A burner 8' is located in the base at the bottom of the flue and is supplied with air by draft pipes 7' mounted on the base. Radial tubes 9' extend across the flue from the inner shell to the outer shell.

15 The forms of the invention shown in the drawings are merely for the purpose of illustration, and it is understood that the invention is not to be limited thereto. A heater constructed in accordance with this invention will be compact, comparatively light in weight, and easy to handle.

20 It is also understood that the heater may be made of tin, sheet metal, or any other suitable material, and that various changes 25 in shape and dimensions, as well as modifications, may be made without departing from the spirit of the invention.

What I claim, is:

30 1. In a water heater, the combination of a base constituting a combustion chamber, a gas burner disposed in the base, an inner shell extending upwardly from the base, an outer shell extending upwardly from the

base, a plurality of radial tubes disposed between the inner and outer shells, and draft 35 pipes mounted on the said base.

2. In a water heater, the combination of a hollow base, a gas burner disposed in the base, an inner shell mounted on the bottom of the base, an outer shell mounted on the 40 top of the base, said outer shell being disposed inwardly of the edge of the base thereby leaving a margin around the top of the base, a plurality of radial tubes disposed between the inner and outer shells, and upright draft pipes mounted on the marginal portion around the top of the base.

3. In a water heater, the combination of a hollow base, a gas burner disposed in the base, a flange depending from the base, a 50 plurality of ports in the flange, an inner shell mounted on the base, an outer shell mounted on the base, a plurality of radial tubes disposed between the inner and outer shells, and draft pipes mounted on the base.

4. In a water heater, the combination of a base having a relatively large vertical channel extending through the bottom of the base and a relatively large entrance for admitting water into the channel, a gas burner disposed in the base, an inner shell mounted on the base, an outer shell mounted on the base, a plurality of radial tubes disposed between the inner and outer shells, and draft pipes mounted on the base.

CHARLES F. WILSON.
